1

This invention relates to electron discharge tubes and circuit arrangements therefor and more particularly to discharge tube apparatus of the electron velocity modulated type.

Electron velocity modulated tubes are in general preferred to ordinary triode or tetrode tubes for the generation or amplification of very short waves such as decimeter and centimeter waves but while they have the advantage of giving great power known velocity modulated tubes are much less convenient to use than ordinary tubes such as triodes on long waves for which use they present a number of disadvantages.

Firstly known tubes of the kind referred to incorporate oscillatory circuits in the form of resonant cavities which constitute part of the tube structure and often indeed constitute part of the evacuated envelope of the tube. Such a construction while presenting material advantages for very short wave working also, however, has the following defects:

(1) A resonant oscillatory circuit forming part of the tube structure cannot be changed and the range of adjustment of operating wave lengths is accordingly very small and involves mechanical or electrical distortion of the oscillatory circuit. This is difficult to achieve satisfactorily if the circuit forms an integral part of the envelope structure.

(2) Such tubes cannot be made as general purpose tubes but must be specialized for their intended uses. Thus, for example, in an oscillator, the reaction elements form an integral part of the structure and being in the vacuum, practically cannot be reached for modification. A tube designed as an oscillator, therefore, is not suitable for use as an amplifier.

(3) The power produced in the oscillatory circuits is led off by a line which might be required to take any of a variety of forms, that is, bifilar, co-axial, hollow metallic wave guide, and so on. As however the circuits are fixed and part of the structure it is impossible to alter them to adapt them to different forms of feeder so that a tube must be designed for a pre-selected form of feeder. As the forms of feeder vary with the utilization apparatus in question—one form being best for an aerial feed and another for feeding a radio horn, for example—this means further specialization of tube design.

This invention seeks to provide a form of construction of a velocity-modulated valve which shall avoid these disadvantages and give flexibility of use comparable to that of an ordinary triode or like tube on long waves.

2

The essential characteristic of the invention lies in separating the elements of the tube proper and the elements of circuits into two units of independent construction which can be easily separated and dismantled from one another so that different circuits of different shapes and adapted for different requirements may be employed in exchange with one another in conjunction with the elements of the tube proper. An arrangement in accordance with this invention thus comprises two parts, viz: the electronic tube proper and the associated circuits.

The invention is illustrated in and further explained in connection with the accompanying drawings, Figures 1 to 7.

Referring to the drawings an arrangement in accordance with this invention comprises two parts constructed as follows: The electronic tube proper has a cylindrical glass envelope member 20 A, provided with welded metallic electrodes and of a diameter reduced to the minimum dimensions necessary to contain the well-known cylindrical electron beam of a velocity modulated tube. Within the envelope of the tube is a cathode 25 1 and associated heater 1', an intensity controlling grid 2 and two velocity-modulating grids 3 and 4 which are in effect extended by two cylindrical metal parts 5 and 6 sealed to the glass in such manner that the high frequency electrical 30 connections may be made in a continuous fashion through the whole periphery of a ring 7 or 8 protruding from the glass. A glass cylinder also forming part of the envelope insulates the two grids from one another. These two electrodes 35 are so shaped in accordance with the invention, as to allow the glass to be at a safe distance from the space between the two grids 3 or 4, where an intense high frequency field exists, so that harmful dielectric loss is not introduced 40 while nevertheless the diameter of the tube is kept as small as possible.

The metal part 6 encloses the drift space in which electrons, removed from the action of the high frequency field, collect in bunches. A 45 similar construction is adopted for the second pair of grids 10, 11, the former 10 being fixed to the part 6 and the latter 11 being fixed to a metal electrode 12 which finally receives the electrons. The electrode 12 is cooled by means not 50 shown and may be cooled by radiation or by a current of water or air.

In the modification shown in Figure 2 which is intended for lower powers, the grids 3 and 4 are replaced by a slit 13 cut in the circuit at 55 the extremity of the bulb as is shown, and the

tube itself has a simplified shape. At reduced powers losses in the glass may be disregarded at the positions of the grids 3 and 4 where the high frequency voltage is weak and little trouble is experienced due to the glass at high frequency. The other parts in Figure 2 are marked with the same references as in Figure 1.

The tube structure does not include any oscillatory circuit element. Such elements are formed as second units which may take extremely varied shapes, a preferred one of which will be described.

A tube as described above will operate in conjunction with resonators of various shapes, for example, the well known toroid resonators. Such resonators have been indicated in position in Figures 1 and 2. However, research has evolved a resonator which will now be described and which has the following important advantages:

(a) It is electrically and mechanically well adapted to the tube.

(b) It permits of a wide variation of wave lengths.

(c) It is easy to couple to cylindrical feeders of rectangular section which are convenient in many applications such as for supplying traveling waves to radiating horns.

The main feature of these circuits, which form another part of this invention, is that of adapting the mechanical and electronic symmetry of the circuits, not to that of the cylindrical exciting beam, but to that of certain feeders, consisting of hollow metallic guides of rectangular section which serve to conduct the high frequency exciting energy and to conduct away energy amplified by the tube. For this purpose the resonators take the shape of rectangular boxes B, of length l , breadth a , and depth b . Figure 3 is one example. One of the walls is movable and formed by a piston 13 by which the length l and thus the resonant wave length of the resonator can be varied. The wall 14 facing the movable piston is pierced by a rectangular slot 15 which serves to couple the resonator to an external load through the medium of a tube whose rectangular section is varied over a certain length in order to connect it to a rectangular section feeder of constant section without the production of stationary waves. The width of the slot 16 may be adjusted in order to adapt the load to the resonator. The resonator is thus easily adapted to the supply of this type of feeder.

The resonator is also pierced by two holes 16, 17 in its walls so as to allow the tube of the invention to pass through. Suitable metal joints ensure contact between the walls 16 and 17 and the rings 7, 8 or 12 which are connected to the tube electrodes. The position of the common axis of the holes in the walls 16 and 17 is chosen in relation to the electron beam current in accordance with well known principles so as to adapt the impedance of the cavity as measured between the two centers in question to the impedance of the beam.

Figure 4 shows a resonator according to the invention assembled around the cylindrical envelope of a tube A as already described.

A number of assemblies of circuits with the tubes according to this invention will now be described.

(a) Amplifier.

Figure 5 shows an arrangement with two circuits B, B' and a tube A adapted to operate as a repeater amplifier at the end of a section of a rectangular wave guide to amplify the power from this feeder and deliver amplified power to

a second section of feeder or guide. The advantages of the construction of this invention will be evident from examination of this figure. The construction of the feeders and resonators remains fixed. The tube, on the other hand, which wears out more rapidly, may easily be changed without disarranging the resonators very much. The adjustment of the resonators after changing the tube is easy and only involves a slight adjustment of the position of the pistons by means of the screws 18 and 19.

The same amplifier may be adapted for co-axial feeders. The slot 15 is then omitted and a coupling loop 20 provided on the wall 21 at the end of the co-axial feeders as in Figure 6.

The component parts of this invention lend themselves readily to the assembly of an oscillator. Figure 7 shows an oscillator so constructed and adapted to supply a rectangular feeder 23. A loop 22 ensures reaction coupling between the two resonators 24 and 25 of the amplifier. The resonator 25 for the grids 3 and 4 is closed. The resonator 24 for the grids 10 and 11 supplies the feeder 23 through a slot.

Our invention is applicable in ultra-high frequency and super-high frequency bands and has been found to be highly efficient in operation. We realize however that modifications in details may be made and we desire that it be understood that no limitations upon our invention are intended other than may be imposed by the scope of the appended claims.

What we claim is:

1. A velocity-modulation tube of cylindrical form provided on its external surface with annular velocity modulating electrode outlets, a hollow resonator in the form of a rectangular parallelepipedal box equipped with circular holes through which the body of the said tube passes and whose edges establish contact with the said electrode outlets.

2. A velocity-modulation tube of cylindrical form provided on its external surface with annular velocity modulating electrode outlets, a hollow resonator in the form of a rectangular parallelepipedal box equipped with circular holes through which the body of the said tube passes and whose edges establish contact with the said electrode outlets, a wall of said box being movable and connected with means for pushing it in adjustably in piston-like fashion.

3. A velocity-modulation tube of cylindrical form provided on its external surface with annular velocity modulating electrode outlets, a hollow resonator in the form of a rectangular parallelepipedal box equipped with circular holes through which the body of the said tube passes and whose edges establish contact with the said electrode outlets, a wall of said box including a slot, and a hollow wave guide connected with said slot.

4. A velocity-modulation tube of cylindrical form provided on its external surface with annular velocity modulating electrode outlets, a hollow resonator in the form of a rectangular parallelepipedal box equipped with circular holes through which the body of the said tube passes and whose edges establish contact with the said electrode outlets, a wall of said box including a hole connected with the external conductor of a coaxial line whose internal conductor ends in a loop penetrating into the box.

5. A velocity-modulation tube of cylindrical form provided on its external surface with annular electrode outlets for propagating an elec-

tron beam, a hollow resonator in the form of a rectangular parallelepipedal box equipped with circular holes through which the body of the said tube passes and whose edges establish contact with the said electrode outlets, the position of these holes being predetermined by the condition that the impedance of the resonator is adapted to the impedance of the electron beam of the velocity-modulation tube.

6. An amplifier for waves of the ultra-high frequency and super-high frequency bands comprising a velocity-modulation tube of cylindrical form equipped on its external surface with an-
10 nular electrode outlets, two hollow resonators each in the form of a rectangular parallelepipedal box equipped with circular holes through which the body of the said tube passes and whose edges establish contact with the said electrode outlets, the first resonator being coupled with means of excitation and with the incoming circuit of the tube, and the second resonator being coupled with the outgoing circuit of the tube and with means for tapping energy.

7. An oscillator for waves of the ultra-high frequency and super-high frequency bands comprising a velocity-modulation tube of cylindrical
15

5 form equipped on its external surface with an-
nular electrode outlets, two hollow resonators each in the form of a rectangular parallelepipedal box equipped with circular holes through which the body of the said tube passes and whose edges establish contact with the said electrode outlets, and means establishing a reactive coupling between said two resonators.
